UNITED STATES PATENT OFFICE.

GEORGE E. DOW, OF SAN FRANCISCO, CALIFORNIA.

ENGINE-GOVERNOR.

SPECIFICATION forming part of Letters Patent No. 365,508, dated June 28, 1887.

Application filed September 7, 1886. Serial No. 212,944. (No model.)

To all whom it may concern:

Be it known that I, GEORGE E. Dow, of the city and county of San Francisco, State of California, have invented an Improvement in 5 Engine-Governors; and I hereby declare the following to be a full, clear, and exact description of the same.

My invention relates to an improved speed governor or regulator, and is adapted to control the admission of steam, gases, or fluids—such as may be employed in operating different kinds of engines of the reciprocating-piston type—for the purpose of maintaining a uniform speed under variations in pressure or resistance of the load.

The device consists, mainly, in a pair of inverted single-acting plungers operated by the engine to be governed, the action of said plungers being employed, through the medium of 20 a liquid fulcrum, to elevate a weight to which the engine-valve is connected, the arrangement being such that the speed of the engine becomes dependent upon a regulated resistance to the alternate reciprocations of the 25 plungers.

It also consists of certain details of construction and in a novel and effective means of controlling the action of the governor, all of which will be more fully explained by reference to 30 the accompanying drawings, in which—

Figure 1 is a vertical section of my improved governor, shown in the present case connected direct to a balanced steam-valve, R. Fig. 2 is an enlarged vertical section of the 35 cylinder A, showing actuating mechanism through line C D, Fig. 3. Fig. 3 is a cross-section of the cylinder A through the line A B, Fig. 1, showing partial section of the weighted piston B, passages Y Y, port or cavity Z, passage L', and plan of plunger-chambers C C. Fig. 4 is a plan view of the cylinder A, showing the piston B, plungers D D, and links E E removed. Fig. 5 shows one 40 form of its application to a direct-acting steam-pump. Fig. 6 is a modification showing the 45 plungers operating in a reverse direction.

A is a cylinder, preferably placed in a vertical position and partially filled with oil or other suitable liquid, as may be indicated by 50 the glass tube M, said cylinder being provided with a weighted piston, B, which is

fitted to slide freely up and down within certain limits, as hereinafter described. The piston B contains two chambers, C C, within which the plungers D D alternately reciprocate through the medium of the links E E, double-arm crank F, and vibrating arm G, connected to some reciprocating part of the engine to be governed, so that the connected parts G, F, E E, and D D may be operated 55 coincident with the main piston of the engine. The plungers D D contain valves H H, opening upward, so that the plunger descending will allow the oil or other medium to pass freely through, allowing the weight of the 60 plunger to be utilized to overcome the friction of the liquid through the induction-passage of the valves H H, thus providing a compensation for wear and allowing no possibility for lost motion to exist, as the strains upon 65 the internal wearing journals do not reverse. The space I below the piston B, which contains the moving parts that are operated from the outside through the stuffing-box J, has an upwardly-opening valve, K, Fig. 2, the under 70 side of which communicates freely with the space L above the piston B by means of the passage L', the object of the valve K being to allow the piston B perfect freedom to rise, so that it has no resistance to a quick 75 closing movement when the conditions demand it, as will be hereinafter described. The piston B has an upwardly-extended projection, B', which in this case is shown fitted to slide freely through the cover N and connect 80 with the external cross-head, P, supporting, by means of the rods Q Q, the weight O, which is connected to the engine-valve R. Between the chambers C C is a communicating passage, 85 S, in which the valve or screw-plug T is employed for the purpose of adjustment. From each of the chambers C C are circulating-passages U U, communicating with the space L. These passages have screw-plugs V V also, for the purpose of adjustment, though not required, except for extreme ranges of speed and to compensate for an uneven piston movement of the engine to be governed, as hereinafter 90 described. A passage, W, through the piston B, connecting the top space, L, with the bottom space, I, is also provided, and has a screw-plug, X, for the purpose of controlling in 95 100

point of time the descending or admission movement of the governor. The ports or passages Y Y are provided, leading from the chambers C C to the exterior turned or fitted 5 portion of the piston B, for the purpose of engaging with the stationary cavity Z, which at a certain point in the upward movement establishes a supplementary communication between the chambers C C, so that the piston 10 cannot rise beyond the desired limit.

The operation of the apparatus may be described as follows: Assuming the cylinder A to be partially filled with oil or other suitable liquid, so that the piston B is submerged, filling 15 the space I, chambers C C, all passages employed in its operation, together with the chamber L, until the glass tube M indicates the cylinder to be nearly full, the vibrating arm G is to be connected to some reciprocating 20 part of the engine to be governed, so that the plungers D D alternately reciprocate in their chambers C C, said plungers having a positive mechanical connection to the engine-piston, or suitable connections therefrom, so 25 that a coincident movement may be maintained between the engine and the plungers of the governor. The weighted piston B, when not being sustained by the influence of the liquid medium forced by the plungers, will remain seated upon the internal flange or shoulder, A', and in this position the engine-valve R, connected thereto, as shown, will be 30 opened to its fullest extent. When, however, one of the plungers D D, operated by 35 the engine, is pressing upward, the valve H prevents the oil or other liquid from escaping from the chamber C except by means of the passages U and S. While the other plunger is descending freely its chamber C is filled 40 through the combined orifices U S and the upwardly-opening valve H in the plunger. The passages U from each of the plunger-chambers are maintained as separate constant 45 openings, each one of which may be adjusted independent of the other when desired. When the speed of the engine has reached a point where the resistance of the combined orifices U and by-pass S is sufficient to overcome the 50 weight or closing power of the governor, the piston B will rise, closing the valve and cutting off any excess of power that would tend to run the engine faster than desired, and if, on the other hand, any additional load is placed on the engine or a reduction of the pressure, 55 the weighted piston B will descend, opening the valve to supply the required additional amount of power. The by-pass passage S between the chambers C C being regulated by means of the screw-plug T, serves to adjust the 60 speed of the engine when desired, closing to run slower and opening to run faster. If the engine is suddenly relieved of its load, as in the case of a main belt breaking, bursting of a 65 pump or force-main, or in the case of a propeller-engine in rough weather at sea, "racing" is prevented, as the closing movement of the

governor is positive and practically instantaneous. The plungers act directly to raise the piston B from its normal position of working, with any slight acceleration of the speed of the engine, as the orifices U and S create an additional resistance in proportion to the squares of the velocities. The valve K permits the liquid to enter the chamber I freely, so as not to oppose the closing or upward movement of the governor. The passage W, through the piston B, with screw-plug X, serves to regulate the opening movement, giving a steadiness to the apparatus while working in a normal condition. If the governor is connected to an engine that has an uneven movement—such as an unbalanced vertical or some kinds of pumping-engines where the inward and outward movement is run on different average piston speeds—the passage U from the chamber C, 85 into which the plunger D is working in time with the stroke having the less speed, may be adjusted by the screw-plug V, diminishing the discharge-orifice, so as to suit the reduced velocity of its plunger, and thus maintain a 90 steady normal action to the governor without interfering with its sensitiveness, but avoiding the pulsations that would otherwise follow.

As a precaution against accidental injury to the governor, or unusual strains being brought 95 upon any of its parts, the ports Y Y are employed, leading from the chambers C C to the turned or sliding surface of the piston, as shown, together with the stationary cavity Z, suitably placed in the bored surface of cylinder A, so 100 that by no possibility of imperfect adjustment or from any other cause can the piston B rise more than to cause these passages to meet the cavity Z, when a supplementary communication is effected between the chambers C C. 105 The cavity Z is intended to be placed so that the engine-valve will be closed before the ports Y Y communicate ordinarily.

The apparatus here described is simple in construction, not liable to lost motion through 110 excessive use, or other derangements by careless or unskilled management.

It will be seen that the operation of the governor is controlled principally by the valve or screw plug T, and that the valve X or passage 115 W prevents fluctuation while working in a normal condition, and regulates the speed of the opening movement, without in either case affecting the possible instantaneous closing action which is so much to be desired.

Although I prefer the general arrangement of parts and method of operation herein shown, I do not wish to limit myself to this precise construction, as there are many other arrangements of details that may be easily substituted without departing from the essential 125 features of the invention.

In Fig. 6 I have shown the piston B fitted in the lower part of the chamber A, and the pistons or plungers D fitted to move in chambers formed in the main chamber A above the piston B. This extension or elongation of the

piston B passes up through the top of A and connects with the governor-valve in the same manner as before described. The passages, valves, and chambers are only changed in position to suit the different positions of the parts; but in this, as in the other forms, the total reactive force of the governor is sustained by and controlled through the direct reciprocation of the plungers operated by the engine to be governed.

It will be manifest that this governor may also be so constructed as to operate horizontally, instead of vertically, a few simple changes being made to suit the changed positions of parts.

By the construction of this apparatus, with the reciprocating pistons or plungers working in connection with the main piston, and the regulating-passages through which the liquid is forced, it will be seen that when the engine runs at a certain rate of speed the flow of the liquid through these passages will be maintained at such a rate that the main piston will be suspended in a certain position against the pressure of the counterbalancing-weight or equivalentspring, and will remain in such position as long as the engine runs at that rate; but if by any sudden decrease of load or for other reason the engine should begin to run faster, the pistons in the small cylinders would be moved at a correspondingly greater speed; and as the passage could not accommodate the increased flow of liquid it will be seen that the very first movement of one of these pistons at a greater rate of speed would act to raise the main piston bodily, through the medium of the liquid confined above the smaller piston and inside the chamber in the upper part of or connected with the main piston, as this liquid could not escape through the discharge-passages fast enough to allow the small piston to complete its stroke. The main piston thus raised quickly would act through its connections and partially close the valves by which steam is admitted to the cylinder, and would thus regulate the speed of the engine instantly and before it could even complete a full revolution. As the weight of the main piston and the connected weight are supported directly upon the links or pitmen E, which operate the pistons in the smaller cylinders, it will be seen that there can be no lost motion, even although the pins be smaller or become considerably worn, as the whole weight always rests upon the top of these vertically-moving pitmen, and consequently there will be no reverse motions and no wear on these parts, which is very important for the perfect operation of this governor.

Having thus described my invention, what I claim as new, and desire to secure by Letters Patent, is—

1. A governor consisting of a cylinder containing liquid, a main piston moving vertically therein and connected with the supply-valve of the engine, and the smaller alter-

nately-reciprocating pistons operating in corresponding chambers in the main piston, in combination with the upwardly-opening outlet-valves in said pistons and the escape-passages through the main piston, substantially as herein described. 70

2. The exterior cylinder or chamber containing liquid, having a main piston moving therein connected with the steam-inlet valve of the engine, and a weight by which the valve is closed, in combination with the supplemental pistons fitted to chambers within the main piston, with valves and outlet-openings, and the oscillating arm or lever connected with a reciprocating part of the engine, so as to be operated in unison therewith, substantially as herein described. 75

3. The weighted main piston moving in the cylinder containing liquid, and chambers or cylinders in the main piston, within which supplemental pistons are actuated by means of an oscillating arm or lever connected with the reciprocating portion of the engine, so as to move in unison therewith, in combination with passages or openings from the supplemental cylinders to the main cylinder, and adjusting or regulating screw-plugs whereby these openings may be enlarged or diminished, substantially as herein described. 85 90

4. A weighted main piston connected with the engine-valve and moving within a liquid-containing cylinder, the supplemental pistons actuated in unison with the reciprocations of the engine and moving in cylinders within the main piston, the valves opening into the supplemental piston-chambers, and a passage or by-pass connecting the supplemental cylinders and provided with a regulating plug or screw, substantially as herein described. 95 100

5. The weighted piston connected with the steam-inlet valve of the engine and moving within a liquid-containing cylinder, supplemental pistons moving in corresponding chambers within the main piston, and mechanism whereby these supplemental pistons are caused to reciprocate in unison with the movements of the main engine-piston, in combination with a stationary cavity, and passages leading from the chambers of the supplemental cylinders to the stationary cavity, so that when the latter is raised to a certain point communication is opened between the chambers through the stationary cavity, substantially as herein described. 110 115 120

6. A governor consisting of a cylinder containing liquid, a piston fitted therein and connected with the supply-valve of the engine, and smaller alternately-reciprocating pistons operating in corresponding chambers in the main piston, in combination with the inlet-valves and the escape-passages of the actuating-chambers, substantially as herein described. 125

7. In a governor, a cylinder or chamber containing liquid, a piston fitting therein and connected with the supply-valve of the en-

gine, and smaller alternately reciprocating pistons operating in corresponding chambers in the main piston, and by which means the reactive force of the governor is sustained and controlled, in combination with the inlet-valve 5 K and passage L', communicating with the reservoir space L and return-passage W, substantially as herein described.

In witness whereof I have hereunto set my hand.

GEORGE E. DOW.
